UNITED STATES PATENT OFFICE

112,434

DESIGN FOR A NOVELTY DOLL

Meyer Julius Hackman, Chicago, Ill.

Application March 5, 1938, Serial No. 75,618

Term of patent 7 years

To all whom it may concern:

Be it known that I, Meyer Julius Hackman, a citizen of the United States, residing at Chicago, in the county of Cook and State of Illinois, have invented a new, original, and ornamental Design for a Novelty Doll, of which the following is a specification, reference being had to the accompanying drawing, forming a part thereof.

Figure 1 is a front elevational view of the novelty doll showing my new design;

Fig. 2 is a side elevational view of Fig. 1.

The shading represents the contrasting color with the unshaded or white portions of the design.

My design, as illustrated in the accompanying drawing, comprises as its essential features the figure 8 configuration of the face with its contrast against the darkened remainder of the head plus the substantially complete carrying through of the shoulder and upper arm contour to the contrasting flipper-like tips thereof.

I claim:

The ornamental design for a novelty doll, substantially as shown and described.

MAYER JULIUS HACKMAN.
